(57) **CLAIM**

We claim the ornamental design for a direction indicator, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front plan view of a first embodiment of a direction indicator showing our new design;

FIG. 2 is a front plan view of a second embodiment of a direction indicator showing our new design;

FIG. 3 is a front plan view of a third embodiment of a direction indicator showing our new design;

FIG. 4 is a front elevation view of the first embodiment, shown in a position of use on a fall arrester;

FIG. 5 is a front elevation view of the first embodiment, shown in a position of use on a rail shuttle; and,

FIG. 6 is a front elevation view of the first embodiment, shown in a position of use on a rail shuttle.

The dash-dot-dash broken lines depict boundaries of the claimed design within the dash-dot-dash broken line boundaries. The dash-dot-dash broken lines form no part of the claimed design. The fall arrester and rail shuttles of FIGS. 4, 5, and 6 illustrate environment and form no part of the claimed design.
